J. Edson
Force Pump.
N° 26025.   *Patented Nov 8, 1859.*

UNITED STATES PATENT OFFICE.

JACOB EDSON, OF BOSTON, MASSACHUSETTS.

PUMP.

Specification of Letters Patent No. 26,025, dated November 8, 1859.

To all whom it may concern:

Be it known that I, JACOB EDSON, of Boston, in the county of Suffolk and State of Massachusetts, have invented certain new and useful Improvements in Force and Lift Pumps, of which the following is a full, clear, and exact description, reference being had to the accompanying drawings, making part of this specification, in which—

10 Figure 1, is a vertical section through my pump; Fig. 2, a horizontal section upon the line y, y , of Fig. 1; Fig. 3, a plan of the movable box or plunger; Fig. 4, a plan of the valve b , of Fig. 1; Fig. 5, a view of the spring cylinder g . Fig. 6 will be referred to hereafter.

15 To enable others skilled in the art to understand my invention, I will proceed to describe the manner in which I have carried it out.

20 In the accompanying drawings, A, is the body of the pump, down through the center of which descends the tube B, which steadies and guides the piston rod C, and descends 25 so low as to enter the water in the air chamber that any leak around the piston may not empty the air from the air chamber. The piston rod is packed by the cap D in the customary manner.

25 E, is the movable box or plunger through the openings a , in which the water passes from the cylinder to the air chamber G. The openings a , are closed by the circular disk valve b , which plays up and down upon the rod C as the latter is operated. A difficulty has heretofore been experienced with valves of this description arising from the introduction of sand and grit at the point c , between the valve and piston rod, to remedy 30 which evil I employ a cylinder of india rubber g , which surrounds the piston rod, and bears at its upper end upon the shoulder h . The lower end of this cylinder rests upon the valve and holds it down upon its seat at 35 the same time that it firmly grasps the flange f , and thus prevents the admission of sand and grit at the point c , as before stated. In pumps of this character where the stroke is short some time is lost after the plunger commences to rise before the valve falls upon its seat. This is measurably corrected by 40 the spring of the tube g , which forces the plate down upon its seat so soon as the plunger commences to rise.

45 50 Efforts have been made to do away with the water hammer in pumps of this class,

but thus far without entire success. Where an air chamber has been placed upon the induction pipe the difficulty has only been partially remedied owing to the smallness of 55 the passages from such air chambers to the induction pipe and from the latter to the pump cylinder.

60 The second part of my invention has for its object the removal of this difficulty and consists in the peculiar manner in which I have surrounded the pump cylinder with a vacuum chamber or fountain H, the bottom of the cylinder resting upon flanges, whereby a free passage is provided from the induction pipe to the vacuum chamber or fountain through which the water is permitted to flow freely in and out without obstruction and an easy motion of the plunger is thereby secured. This part of my invention will now be described. The pump cylinder I, which is of drawn yellow metal or other suitable composition, is passed through an opening in the partition or division plate K, the joint between the two being secured 65 by molten metal. The cylinder is allowed to project slightly above the plate K, that there may always be a stratum of water retained above the plate, by which means the joint at i , is further secured by the rust 70 which forms at this point. The bottom of the cylinder is forced down upon the flanges L, upon the inclined surfaces of which it adjusts itself and by which it is held in position. An abundant passage way is thus 75 afforded between the flanges L and beneath the bottom of the cylinder for the water in and out of the chamber, as before described. A vacuum chamber thus arranged is particularly applicable to a pump of short 80 stroke, as it acts as a fountain to supply the pump readily with water, and enables me to employ a smaller induction pipe than could otherwise advantageously be used. When the induction pipe is secured to the 85 body of the pump by means of a flange and clamp, if the screw which confines the clamp to the pump be brought down unequally one side of the flange is liable to be sprung off from the pump and the joint is not tight.

90 95 100 105 110 To remedy this is the object of the third part of my invention, which consists in the use of two bearing points which project from opposite sides of the clamp and bear upon opposite sides of the flange; these points are seen at m , Fig. 6, which represents a plan and side view of the clamp.

which secures the induction pipe to the pump. If now an unequal strain be put upon either of the screws S, the clamp is allowed to pivot upon the points *m*, and 5 the induction pipe is thus enabled to adjust itself to its seat.

T, is a plug by means of which the pump may be changed from a lift to a force pump.

U, is a basin through which water may 10 at any time be introduced to start the pump.

What I claim as my invention and desire to secure by Letters Patent is—

1. The peculiar manner in which I support the cylinder upon the flanges L, in combination with the vacuum chamber H for 15 the purpose of insuring an unobstructed passage between the said chamber and the induction pipe below the valves in the man-

ner and for the purpose substantially as herein set forth.

20

2. I claim the manner herein described of securing the induction pipe to the pump by means of the projecting bearing points *m*, operating in the manner substantially as herein set forth.

25

3. I claim the within described combination and arrangement of the division plate or partition K, and the cylinder I, whereby the body of the pump is divided into two distinct chambers the one serving as an air 30 or water chamber and the other as a vacuum chamber as set forth.

JACOB EDSON.
